(57) CLAIM

The ornamental design for a jar, as shown and described.

DESCRIPTION

FIG. 1 is a top perspective view of a first embodiment of a transparent jar, embodying my new design;

FIG. 2 is a bottom-perspective view thereof;

FIG. 3 is a front-elevational view thereof;

FIG. 4 is right-side-elevational view thereof;

FIG. 5 is a top-plan view thereof;

FIG. 6 is a bottom-plan view thereof;

FIG. 7 is a top perspective view of a second embodiment of a non-transparent jar, embodying my new design;

FIG. 8 is a bottom-perspective view thereof;

FIG. 9 is a front-elevational view thereof;

FIG. 10 is right-side-elevational view thereof;

FIG. 11 is a top-plan view thereof; and,

FIG. 12 is a bottom-plan view thereof.

In FIGS. 1-6, the oblique-shaded lines shown in the drawings represent that the jar is transparent.
